UNITED STATES PATENT OFFICE.

CHARLES C. HOCKMAN, OF DORCHESTER, MASSACHUSETTS, ASSIGNOR TO LANSTON
MONOTYPE MACHINE COMPANY, OF PHILADELPHIA, PENNSYLVANIA, A CORPO-
RATION OF VIRGINIA.

CUTTING MECHANISM.

1,193,389.

Specification of Letters Patent.

Patented Aug. 1, 1916.

Original application filed December 11, 1914, Serial No. 876,661. Divided and this application filed March 26, 1915. Serial No. 17,233.

To all whom it may concern:

Be it known that I, CHARLES C. HOCKMAN, a citizen of the United States, residing at Dorchester, in the county of Suffolk and 5 State of Massachusetts, have invented certain new and useful Improvements in Cutting Mechanism, of which the following is a specification.

In the well-known monotype machine the 10 matter is composed by striking the proper keys of the key-board, each key struck producing perforations in a paper ribbon. This paper ribbon is associated with mechanism of the casting machine whereby it controls automatically the character the casting machine will produce. The key-board includes justification keys, and at the end of 15 the line, or at any desired point in it, the compositor at the key-board justifies the line, or portion of it by striking the justification keys. Thus the ribbon when placed in the casting machine compels the latter to cast type in justified lines exactly as composed by the compositor at the key-board. 20

In making up the matter it frequently becomes necessary to insert leads between the lines in order to secure required spacing. The monotype machine has been provided with an attachment for casting metal into strips 25 of continuous lengths, these strips being later cut or sawed by hand into sections of appropriate lengths for the leads, that is to say, into lengths according with the lengths of the lines which are to be separated 30 from each other thereby. The strip casting attachment referred to is so arranged that it can be applied to the type casting machine by removing the type casting mold or matrix and substituting the 35 strip casting mold therefor, and by it a strip of continuous length is formed of a series of separately cast sections whose ends are integrally united with each other, the attachment having a molding chamber into 40 which molten metal is squirted in successive jets with intervening pauses by the parts of the type casting machine which in the type-casting operation squirts the molten metal into the type mold, the sequence of squirt- 45 ing operations or the temperature of the molten metal being so arranged in the formation of the strips that the end of the pre-

viously formed section will be melted and united integrally with the newly forming section. The molding chamber, moreover, 55 has one of its walls formed by a gate or blade which confronts the end of the formed section and is spaced therefrom while molten metal is being injected into the molding chamber, the distance between the end of 60 the formed section and the inner end of the gate or blade determining the length of the section to be formed. This gate or blade is reciprocated by a lever which derives movement from the type carrier cam of the type 65 casting machine, its movement in one direction being away from the formed section of strip and opening the chamber for a supply of molten metal and occurring immediately before the metal is squirted into said 70 chamber, and its movement in the other direction forcing the strip away from the mold. The throw of this gate or blade is adjustably regulated in a suitable way to accord with the length of the sections of the 75 strip which are to be cast at each operation of the casting mechanism. This manner of producing the leads necessitates manual labor in the cutting or sawing of the strips 80 into leads of the required lengths and moreover results oftentimes in the production of useless leads, as it frequently happens that the leads and rules when cut by hand are bent to an extent which prevents their being 85 used.

This invention generically relates to cutting mechanism but more particularly, though not exclusively, relates to a cutting mechanism having parts so organized that it is adapted to be associated with a monotype casting machine and to be operated by or under control of appropriate parts, as hereinafter more particularly set forth: it being one of the important ends of the present invention to provide a cutting mechanism which is adapted to be so correlated with a strip casting mechanism—of the kind hereinbefore referred to, for example—that the strips of metal while being cast will be cut into appropriate length for use as leads 90 or rules, automatically.

Others of the important aims of the present invention are to incorporate certain new and useful features in the construction of

the cutting mechanism whereby it becomes most practicable for the purposes for which it is most especially intended.

In the accompanying drawings I have 5 illustrated the preferred embodiment of the invention and exemplified its correlation with a monotype casting machine: but I would have it understood that this is merely exemplary and that important changes in 10 the details may be made and that the invention may be otherwise and variously embodied without departing from its spirit or the scope of the subjoined claims.

In the accompanying drawings, wherein 15 like characters of reference indicate similar parts in the various views: Figure 1 is a diagrammatic representation of a casting and cutting mechanism embodying the present improvements; several of the parts 20 thereof being parts which are now employed in the well known monotype casting machine; Fig. 2 is a plan view of the cutter mechanism forming the present invention, together with certain parts of a monotype 25 machine which are associated therewith; Fig. 3 is a side elevation of the parts shown in Fig. 2; Fig. 4 is a detail plan view of the cutter mechanism, on a larger scale than the preceding figure; Fig. 5 is a vertical section 30 on the line 5—5 of Fig. 4; Fig. 6 is a detail plan view of the cutters with the cover plates removed; Fig. 7 is a detail plan view showing the fixed cutting member and the guide for the movable cutting member, the latter 35 cutting member and the cover plates being removed, Fig. 8 is an end view of the movable cutting member; and Fig. 9 is an inverted plan view of the latter member.

The cutting mechanism herein exemplified 40 includes two relatively movable strip cutting and guiding members A and B having channels *a* and *b* respectively through which is fed the strip of metal X or other article to be cut. Preferably, the member A is fixed 45 and the member B mounted to reciprocate across the end of the member A, the member B having an inclined cutting edge *b'* which co-operates with the edge *a'* of the member A in the severing of the strip X, the operation being substantially a shearing one upon 50 the strip, as will be apparent. The movable member B is guided in its reciprocations, preferably by strips *b*² seated in recesses *b*³ formed in the lower surface of said member, 55 and stops *b*⁴ are provided to engage the ends of the member B and limit its movement. In practice, the member A is preferably 60 formed of two blocks 10 and 11 spaced to provide the channel *a* and connected with each other by a plate 12 mounted upon their upper surfaces, the said blocks having beveled ends 10^a and 11^a arranged to form a gradually-reducing mouth leading to said channel. The member B in practice is also 65 preferably formed of two blocks 13 and 14

spaced to provide the channel *b* and having a top plate 15 suitably secured to the blocks and connecting them with each other.

The members A and B are preferably mounted on a suitable base plate D having 70 front and rear spaced elements 16 and 17 which guide and support the strip. The front element 16 is preferably provided with a projection 18 which extends over the movable member B and holds it down in its 75 proper plane of operation.

The cutting mechanism herein exemplified includes, in addition to the parts just described, an appropriate frame by which it is adapted to be mounted upon rods, as *e*, *f*, 80 such, for example, as those which project from the galley stand E and support the galley pan support F of the at present well known monotype casting machine. When the herein exemplified cutting mechanism is 85 applied to such a machine the galley pan support F is removed from the machine in order to afford room for the cutting mechanism, and after the cutting mechanism has been applied, the galley pan support may be 90 replaced on the rods *e*, *f* in the position shown best in Fig. 2. The frame comprises side members 20 and 21 connected with each other by cross pieces 22, and is preferably mounted on the rods *e*, *f* in a manner which 95 permits the cutting and guiding members to be adjustably fixed in position to receive the strip X and sever the same. Such a connection is preferably effected as follows: The members 20 and 21 are formed with 100 openings 20^a and 21^a which receive the rod *e* and by which the frame is pivotally mounted on said rod. Said members also have open ended slots 20^b and 21^b which receive the rod *f*. Adjacent to the openings 20^a 105 and 21^a are screws 23, 24 which extend upwardly against the rod *e*, and adjacent to the openings 20^b, 21^b are screws 25 and 26 which extend downwardly through the members 20 and 21 into engagement with the rod *f*. 110 These screws co-operate with each other, by their engagement with the rods, to raise or lower the cutter to a predetermined height.

The cutting mechanism further embodies 115 a means by which the movable member B may be operated automatically. The means herein illustrated are of a character which well adapts the cutting mechanism to be associated with a monotype casting machine and to be operated by certain parts of the 120 latter. Hence I have shown in a conventional or diagrammatic way such parts of the monotype casting machine as are, or may be, utilized without, however, intending thereby to restrict the invention to this particular application thereof. The parts referred to are certain elements of the justifying mechanism and also the galley stand E and galley pan support F. As is well known 125 to those familiar with the monotype casting 130

machine there is employed in such machine a cross girt, indicated at G, having a perforation g, from which an air pipe H leads to a chamber h in which is an air pin I, the 5 said air pin operating upon a bell crank J one of whose arms is so correlated with a justification wedge lever arm K that it pushes the said arm K into operative relation with a centering pin lever L which is 10 operated positively by cams M mounted on cam shafts M' and raises the justification wedge lever arm K when the latter has been connected with it as described. This raising of arm K causes the same to press the galley 15 trip rod N and this rod, in the monotype casting machine, operates upon a trip lever O. The latter in turn shoving the line of type forward. In the machine referred to there is also a suitable source of supply of 20 compressed air, not shown, which air operates the air pin I under control of operations in a paper ribbon, or "paper tower", the ribbon being indicated at P. When the machine referred to is employed for operating the cutter mechanism it is preferred to disconnect the galley trip rod N from the trip lever O, this being conveniently accomplished merely by adjusting the set screw o (see Fig. 2) away from the end of the galley 25 trip rod, it being understood that in these machines the set screw is normally adjusted in the end of a trip lever so that its end will contact with the trip rod and thereby cause the trip lever to be operated by the 30 trip rod.

In the herein exemplified form of the invention the cutter mechanism is provided with a lever 27 which is fulcrumed at 28 on the galley stand E and has one of its 35 ends provided with a lateral arm 29 which is arranged in the path of movement of the galley trip rod N. The other end of the lever 27 is pivotally connected at 30 to an arm 31 which in turn is connected to the movable member B of the cutter. Preferably, the end of the arm 31 adjacent to the end of the cutter member B is bent downward as shown at 32 in Fig. 5 and is provided with a rearwardly extending blade 40 33 having a slot 34 through which projects a pin 35 rising from the upper surface of the member B, the connection between the arm 31 and the member B being thereby of a lost-motion nature, it being noted that 45 the downwardly bent portion 32 is not fastened to the member B. A retractile spring 36 is connected to the pin 35 and to a pin 37 on the plate 33 and effects the forward movement of the member B when the latter 50 has been pressed rearward by its actuating levers like movement of the said levers being effected by a retractile spring 38 which connects the end of the arm 31 with one of the cross members 22 of the frame. 55 It will now be apparent that when the galley trip rod N is operated it will by its engagement with the projection 29 from the lever 27 press the said lever in a direction which moves the member B transversely across the end of the member A, the cutting 60 edges a' and b' of said members coöperating during such movement to cleanly sever from the strip X a section thereof of a length appropriate for use as a lead or rule, the operation of the said galley trip rod being controlled by perforations in the ribbon P. When the movable member B has been moved to the rear by the operation of the arm 27 it is restored to its former position by the spring 36, the said lever 27 being 65 similarly restored by the spring 38, ready for another cutting operation. The lost-motion connection between the arm 31 and the cutting member B enables the latter to traverse a straight guided path and the 70 means herein described for restoring such cutting member and its actuating lever 27 and arm 31 to their forward position ready for another operation are of advantageous nature particularly when the mechanism is 75 intended for use as a part of a monotype casting machine.

The strip casting mechanism may be of any suitable kind, a suitable one for the purpose being the one which is now supplied to be attached to the type-casting machine when it is desired to cast strips for conversion into leads or rules. In the strip-casting attachment referred to the mold C is so arranged that it may be removably applied to the type-casting machine (the type mold of the latter being removed when the mold C is being used and replaced when the casting of type is again to be performed by the machine) the said mold C when in place on the machine being connected to the pumping mechanism from which it receives the supply of molten metal, the latter mechanism being the one which supplies molten metal to the type-casting mold when the machine is casting type. The strip mold C has a reciprocator gate or blade c² whose inner end forms the rear wall of the molding chamber c'. This gate or blade is reciprocated by means which are well known as a part of the type casting machine and are used in the hereinbefore referred to attachment for casting strips. I consider it to be unnecessary to particularly illustrate or describe said means but have shown the same diagrammatically, c² indicating the type carrier cam lever which is positively operated by the type carrier cams c¹ (the latter in practice being mounted on the same shafts as the cams M), the said type carrier cam lever having a lost-motion connection with the gate or blade c², the gate traveling ordinarily about one-half inch while the throw of the lever is considerably greater. The extent of the lost motion may 100 105 110 115 120 125 130

be regulated as required to variably determine the length of movements of the gate or blade, by varying the distance between the nuts c^3 , the said nuts being adjustable for this purpose.

The front wall of the mold C is the section of lead strip previously cast and to which it is desired to cast another section. In operation molten lead is squirted into the chamber c' when the gate or blade c^2 is in retracted position and after the metal has been allowed to cool slightly and has become united to the end of the previously cast section, the gate or blade c^2 is automatically moved forward, forcing the strip X out from the mold, toward the cutting mechanism, after which the gate or blade is again retracted and the chamber is opened to receive another charge of molten metal, the phases of movements of the gate or blade c^2 being properly timed with relation to the operation of the pump which forces the molten metal into the chamber c' by means which are well known as a part of the monotype machine.

The intervals between the operations of the cutting mechanism is determined by the distance between the perforations in the ribbon P and in turn control the length of the severed sections which respectively constitute a lead or rule.

In the composing machine at present used for producing the perforations in the ribbon employed for controlling the operation of the casting and justifying mechanism of the type casting machine there is a blank key, so called. The operation of this key feeds the ribbon but does not perforate the same. In producing the perforations in the ribbon P for controlling the operation of the cutting mechanism, the composer strikes the blank key the number of times which accords with the intervals desired between the perforations and then strikes the justification key, the latter producing the perforation; he then again strikes the blank key the required number of times, following this with another operation of the justification key, and so on until the required number of perforations arranged at predetermined intervals have been produced in the ribbon for the purpose of casting the required number of rules. For the purpose of illustration, assuming that leads or rules five inches long are to be produced and that each operation of the blank key represents a distance of one-half inch, it will be apparent that the blank key is struck ten times between each striking of the justification key.

The casting operations must be so correlated with the cutting operations that the latter will occur only when the required length of lead has been cast into strip form and, moreover, must take place during the

pauses of the step-by-step feeding of the strip by the gate c^2 . Hence the length of reciprocatory movements of the gate is so arranged that each section cast will be an even divisor of the length of lead or rule required, it being remembered that the length of each section of the strip cast accords with the movement of the gate as does the length of each feeding movement of the strip: the cutting occurring during the non-feeding movements of the gate or while the gate is stationary.

This application is a division of my prior application Serial No. 876,661, filed December 11, 1914.

Having now described the invention what I believe to be new and desire to secure by Letters Patent, is:—

1. A cutting mechanism comprising relatively movable cutting members having channels to receive the material to be cut and coöperating cutting edges adjacent the channels and a lever mechanism for operating the movable member transversely of the channels, the lever mechanism comprising a member having a lost-motion operating connection to the movable cutting member.

2. A cutting mechanism comprising relatively movable cutting members having channels to receive the material to be cut and coöperating cutting edges adjacent the channels and a lever mechanism for operating the movable member, the lever mechanism comprising a member having a lost-motion connection to the movable cutting member and the said connection including a spring.

3. A cutting mechanism comprising a movable cutting member and a means for operating the same, the operating means including an actuating lever and an arm connected to the lever and having a lost-motion connection with the cutting member, the lost-motion connection including a spring.

4. A cutting mechanism comprising a movable cutting member and a means for operating the same, the said operating means including an actuating lever, an arm having connection with the lever and cutting member and a returning spring.

5. A cutting mechanism comprising a movable cutting member and a means for operating the same, the said operating means including an actuating lever, an arm having connection with the lever and cutting member and a returning spring, the connection between the arm and cutting member being of a lost-motion nature.

6. A cutting mechanism comprising a movable cutting member and a means for operating the same, the said operating means including an actuating lever, an arm having connection with the lever and cutting member and a returning spring, the connection

between the arm and cutting member being of a lost-motion nature and including a spring.

7. A cutting mechanism comprising relatively-movable cutting members having channels to receive the material to be cut and coöperating cutting edges adjacent the channels, and an operating mechanism for the movable member, the said operating mechanism including a lever, an arm connecting the lever with the movable member and a returning spring.

8. A cutting mechanism comprising relatively-movable cutting members having channels to receive the material to be cut and coöperating cutting edges adjacent the channels, and an operating mechanism for the movable member, the said operating mechanism including a lever, an arm having connection with said lever and also having a lost-motion connection with the movable member and a returning spring.

9. A cutting mechanism comprising relatively-movable cutting members having channels to receive the material to be cut and coöperating cutting edges adjacent the channels, and an operating mechanism for the movable member, the said operating mechanism including a lever, an arm having connection with said lever and also having a lost-motion connection with the movable member and a plurality of returning springs, one of said springs being arranged in the connection between the arm and movable member.

10. In a machine for cutting strips into sections the combination with means for feeding the strip intermittently and allowing the strip to remain at rest between feed movements and for varying the distance the strip is advanced by the feed movements, of means for severing the strip when a predetermined plurality of feed movements have taken place and during an interval between feed movements whereby sections of any predetermined length may be severed.

11. In a machine for cutting strips into sections, the combination with means for feeding the strip intermittently and allowing the strip to remain at rest between feed movements, and an operating mechanism for the feeding means, of a cutter to which the strip is fed adapted to be actuated by the operating mechanism for the feeding means but normally disconnected therefrom and means for connecting the cutter and operating mechanism when a predetermined plurality of feeding movements have taken place, the cutter actuating connections being timed to actuate the cutter during an interval between feed movements and while the strip is at rest.

12. In a machine for cutting strips into sections, the combination with means for feeding the strip intermittently and allow-

ing the strip to remain at rest between feed movements and for varying the distance the strip is advanced by the feed movements and an operating mechanism for the feeding means, of a cutter to which the strip is fed adapted to be actuated by the operating mechanism for the feeding means but normally disconnected therefrom and means for connecting the cutter and operating mechanism when a predetermined plurality of feeding movements have taken place, the cutter actuating connections being timed to actuate the cutter during an interval between feed movements and while the strip is at rest.

13. A cutting mechanism comprising a fixed member having a longitudinal channel, a member movable across one end of the fixed member and provided with a transverse channel, said channels being arranged to receive the material to be cut and having coöperating cutting edges and an operating mechanism for the movable member, including an arm having a lost-motion connection with the movable member.

14. A cutting mechanism comprising a base, a fixed member on said base, having an inwardly contracted mouth at its front end and an internal channel leading from the mouth, a member movable on the base across the rear end of the fixed member and having an internal channel, the fixed and movable members having their adjacent ends formed with coöperating cutting edges contiguous to the channels, the base also having means forming a channel beyond the movable member, and a lever mechanism for operating the movable member.

15. A cutting mechanism comprising a base, a fixed member on said base, having an inwardly contracted mouth at its front end and an internal channel leading from the mouth, a member movable on the base across the rear end of the fixed member and having an internal channel, the fixed and movable members having their adjacent ends formed with coöperating cutting edges contiguous to the channels, the base also having means forming a channel beyond the movable member, a lever mechanism for operating the movable member, said mechanism including an arm having a lost-motion connection with the movable member and an actuating lever having connection with said arm.

16. A cutting mechanism comprising a base, a fixed member on said base, having an inwardly contracted mouth at its front end and an internal channel leading from the mouth, a member movable on the base across the rear end of the fixed member and having an internal channel, the fixed and movable members having their adjacent ends formed with coöperating cutting edges contiguous to the channels, the base also having

- means forming a channel beyond the movable member, a lever mechanism for operating the movable member, said mechanism including an arm having a loose connection with the movable member, a spring forming part of such connection, and operating means for the arm.
17. A cutting mechanism comprising a base, a fixed member on said base, having an inwardly contracted mouth at its front end and an internal channel leading from the mouth, a member movable on the base across the rear end of the fixed member and having an internal channel, the fixed and movable members having their adjacent ends formed with coöperating cutting edges contiguous to the channels, the base also having means forming a channel beyond the movable member, a lever mechanism for operating the movable member, said mechanism including an arm having a loose connection with the movable member, an actuating lever having connection with the arm, and a plurality of returning springs, one of said springs being arranged in the connection between the arm and movable member.
18. A cutting mechanism comprising relatively movable cutting members having channels to receive the material to be cut and coöperating cutting edges, an arm having an angular end arranged to bear against a side of the movable member, the arm also having a slotted projection above the movable member, a spring having connection with the arm and movable member, and an actuating means connected to the arm.
19. A cutting mechanism comprising relatively-movable cutting members having channels to receive the material to be cut and coöperating cutting edges, an arm having an angular end arranged to bear against a side of the movable member, the arm also having a slotted projection above the movable member, a spring having connection with the arm and movable member, and an actuating means for the arm, the said actuating means including a spring and a lever.

In testimony whereof I affix my signature in presence of two witnesses.

CHARLES C. HOCKMAN.
